UNITED STATES PATENT OFFICE

HARRY GLASSMAN, OF NEW YORK, N. Y.

DESIGN FOR LADIES' PAJAMAS

Application filed May 17, 1930. Serial No. 35,677. Term of patent 3½ years.

To all whom it may concern:

Be it known that I, HARRY GLASSMAN, a citizen of the United States, and a resident of New York city, borough of Brooklyn, in the county of Kings and State of New York, have invented the new, original, and ornamental Design for Ladies' Pajamas, of which the following is a specification.

Reference is to be had to the accompanying drawings forming part thereof wherein—

pair of ladies' pajamas showing my new design, the same being illustrated on a figure indicated by dotted lines;

Figure 2 is a rear perspective view of the pajamas shown in Figure 1, the same being illustrated on a figure indicated by dotted lines.

I claim—

The ornamental design for ladies' pajamas substantially as shown and described.

HARRY GLASSMAN.
